ST. CLAIR EDE

FRAME FOR STRETCHING AND SUSPENDING HIDES

Filed March 18, 1925

INVENTOR,
St. Clair Ede,

BY

Geo. P. Kimmel.

ATTORNEY.

UNITED STATES PATENT OFFICE.

ST. CLAIR EDE, OF DUBUQUE, IOWA.

FRAME FOR STRETCHING AND SUSPENDING HIDES.

Application filed March 18, 1925. Serial No. 16,422.

This invention relates to a frame for stretching and suspending hides in stretched position, and is designed primarily for use in connection with an apparatus for stretching hides as disclosed in my application, Serial Number 16421, filed March 18, 1925, but it is to be understood that a frame in accordance with this invention, can be employed with any construction of hide stretching apparatus for which it is found applicable, and the invention has for its object to provide, in a manner as hereinafter set forth, a frame of the class referred to, having means coacting with suitable supports for revolvably, horizontally and vertically supporting the frame when occasion requires, and further providing the frame with an adjustable hide stretching element and with means for maintaining the hide stretching element in adjusted position, and further with means coacting with a hanger to provide for the vertical suspension of the frame with the stretched hide thereon.

Further objects of the invention are to provide, in a manner as hereinafter set forth, a frame for stretching and suspending hides, which is simple in its construction and arrangement, strong, durable, thoroughly efficient and convenient in its use, readily assembled, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a top plan view of the stretcher frame.

Figure 2 is a section on line 2—2, Figure 1.

Figure 3 is a section on line 3—3, Figure 1.

Referring to the drawings in detail, a hide stretching frame, in accordance with this invention, comprises two pair of end

bars and the end bars of one pair are indicated at 1, 2, and those of the other pair at 3, 4'. The bars 1 and 2 are arranged in superposed relation, but spaced from each other, and a similar arrangement is set up with respect to the bars 3 and 4'. Positioned between the bars of each pair of end bars, at the inner end thereof, is the rear side bar 4 of the frame, and which also constitutes a connecting or suspension bar of narrow form to engage in and coact with a pick-up device, not shown, for the purpose of suspending the frame in vertical position with the hide stretched thereon. The bar 4 is not used for nailing hides thereto.

Arranged between the forward end of the bars of each pair of end bars is the forward side bar 5 of the frame, and said bar 5 projects forwardly of the front ends of the pair of end bars for a purpose to be hereinafter referred to. The bar 4 is secured to each pair of end bars by the hold-fast devices 6, and the bar 5 is secured to each pair of end bars by the hold-fast devices 7. The bar 4 is materially less in width than the width of the bar 5.

The frame furthermore includes a stationary and a shiftable inner bar 8, 9 respectively, and said bar 9 is what may be termed a hide stretcher element. The stationary bar 8 extends between the bars of each pair of end bars and is fixedly secured thereto by the hold-fast devices 10. The shiftable bar 9 is arranged between the bars 4 and 8 and extends between the bars of each pair of end bars. The bar 8 is spaced a slight distance from the bar 5. The bar 9 is provided with a pair of studs 11, 12, which extend therethrough and project from each face thereof. The stud 11 abuts against the inner side edge of the bars 1 and 2, and the stud 12 abuts against the inner side of the end bars 3, 4'. The studs 11 and 12 prevent lengthwise shifting of the bar 9 with respect to the bars 4, 5 and 8, or in other words, the studs connect said bar 9 in position and further act as guides therefor when said bar 9 is shifted relatively to the bars 4 and 8. The bar 9, when shifted to stretch the hide, is maintained in the position to which it has been shifted, and any suitable means may be employed for this purpose, and by way of example, a

holding means for the purpose referred to is illustrated as consisting of two pair of angle irons secured to the outer sides of each pair of end bars and overlapping the 5 same, and coacting with said angle irons is a pair of holding pins.

That pair of angle irons which is secured to the bars 1 and 2 is indicated at 10 13, 14, and each of which is formed throughout 15 out with a lengthwise extending row of openings 15, which register with openings 16, formed in the bars 1 and 2, and through each set of registering openings is adapted 20 to extend a holding pin 17, against which 15 the inner side edge of the bar 9 abuts. That pair of the angle irons which is secured to the bars 3 and 4' is indicated at 18, 19, and each of which is formed throughout with a lengthwise extending row of openings 20, 25 which register with openings 21 formed in the bars 3 and 4', and through each set of registering openings is adapted to extend a holding pin 22, against which the inner side edge of the bar 9 abuts.

25 A reinforcing yoke 23 is positioned centrally of the stretcher frame, overlaps the same, see Figure 1, and has its ends secured by hold-fast devices 24 to the bar 5, and said yoke extends around and opposes the outer 30 side edge of the bar 4 of the frame. See Figure 1. The yoke 23 is only secured to the outer side bar 5 of the frame.

Secured to each end of the stretcher frame, centrally thereof, is a casting, and the casting 35 at one end is indicated at 25, and that at the other end at 26. Each casting has projecting laterally therefrom a polygonal-shaped spindle 27, preferably square, which is adapted to be removably mounted on a 40 flat supporting means, not shown. The said spindles provide for the revolving of the frame, and further so that one of the flat surfaces thereof will act to retain the frame in a vertical or horizontal position. The 45 spindles 27 are arranged at the longitudinal axis of the frame.

A suitable tool, not shown, can be employed for shifting the bar 9 to stretch the frame, and the rear side bar 4 of the frame 50 has secured to its outer side edge wear irons 28. The hide when mounted on the stretcher frame overlaps the bar 5 and is detachably secured by any suitable fastening means to each face of the inner bar 9 which constitutes 55 the hide stretching element, which is shifted by a suitable tool. After the hide has been connected to the stretcher frame and stretched through the medium of the bar 9, the latter is maintained in its adjusted position 60 through the medium of the pins 17 and 22. The bar 4 coacts with a pick-up device, not shown, for the purpose of suspending the frame in a vertical position with the stretched hide thereon. The bar 9, in connection 65 with the shifting means therefor, not

shown, provides for a uniform stretching of the hide when the latter overlaps the bar 5 as both sides of the hide will be stretched simultaneously when the bar 9 is shifted.

Primarily the frame is employed for 70 stretching a hide as a whole. The hide is thrown on the frame hair down, with the center of the back running along the front edge of the bar 5 and one half of the hide is brought down on each side of the frame, but 75 before expanding bar 9, however, the hide is pulled out for length and is then nailed or tacked in place on bars 5 and 8. The reason that bar 5 extends beyond the front 80 ends of the end bars is that very often, the hide is so long that it reaches from end to end of the frame, in which case it would go right around the front ends of the end bars, and if bar 5 did not extend beyond the front 85 ends of the end bars, the corners of the end bars would make a pocket in the hide. As the bar 5 forms a support for the hide, it necessarily follows that it must be of greater width than the bar 4, as the latter is employed for the purpose hereinbefore set forth 90 and is free of the hide.

Furthermore, as the frame is revolvably mounted, the hide can be detachably connected to one side thereof and the frame quickly turned so that the attendant can conveniently attach the other end of the hide to the other side of the frame.

When stretching a non-split or whole hide, the operator has two sides to work with and the manner of stretching the hide with the 100 frame consists in mounting the frame on a support upon which it can be revolved, and after so mounting the frame, supporting the same in a horizontal position with the forward side bar 5 extended towards the operator and the latter then takes a hide and throws it with the fur or grain side down over the frame, with one-half of the hide lying flat on the upper surface of the frame, and the other half hanging down from the 105 outer edge of the bar 5. Three nails are then placed near the tail of the hide. The operator then goes to the other end and pulls the neck out to a position that he considers relative in length to the proper width of the 110 hide. The operator then flops the frame over and the other one-half of the hide spreads itself automatically on the other side of the frame. The operator then steps to the neck and pulls out the neck, pulling 115 in a direction diagonally to the length of the hide, so that the tension would be between the three nails on the butt end of the hide and that part on the neck which the operator is stretching.

The operator then goes to the shoulder and pulls it diagonally also, the line of tension being between the three nails originally put in the butt of the hide in the other side 120 of the frame. The length from the shoulder 125 to

to the rump of the hide should be in proper relation to the width of the hide. The operator now goes to the butt of the hide and places nails in the edge of this part, but up to this time the operator has placed no nails in the stretcher element 9. The operator now places nails in the stretcher element bringing out the front legs to what is considered the proper position with no tension placed on the stretcher element 9, but the operator places the nails to obtain the most perfect shape possible.

After the hide has been nailed on one side of the frame, in the manner as referred to, the frame is flopped over by raising the outer edge of the bar 5. This brings the opposite side of the frame up on which the other half of the hide is lying loose. This half of the hide must then be nailed out in the same manner as the other half and before the stretcher element is shifted. No nails are employed at the center of the hide so that when the stretcher element is operated, the pull is from the nails on the edge of the hide on one side of the frame to the nails on the edge of the hide on the opposite side of the frame. When the stretcher element is operated, both sides of the hide are stretched at the same time. After the nails have been positioned on both sides of the hide, both ends of the stretcher element are engaged by tongues or other suitable means to adjust said element for the purpose of stretching the hide, and any wrinkles that have developed through the pulling of the hide lengthwise disappear on the operation of the stretcher element.

The hide can practically be made any shape by pulling on it lengthwise before the stretcher element is shifted and by placing the nails in the stretcher element at the proper position.

In the case of small leather hides that can be run through the fleshing and putting-out machines without being split into sides, the method would, of course, be the same as is used on furs or whole hides as referred to.

In the stretching of hides that have been cut into sides, the method would be the same, except that the edge of the back of the hide, that is where it has been split, would have to be nailed on the bar 5. One side would be entirely nailed, then the frame would be flopped over and the other side of the leather would be entirely nailed to the stretcher element at the other side of the frame. Then the expansion would take place when the stretcher element is adjusted in the same manner as if one solid hide was being stretched instead of two halves.

By employing the frame in the manner as stated, one is able to save approximately one-third of the cost of material going into a coat, a twenty-five one pound kip will take the place of a forty pound cow hide and the

leather will be shaped so that it will cut advantageously. The legs of the hide practically disappear in the body of the hide. This is accomplished by placing a few nails on each side of the leg where it joins the body. Then when the pressure is placed on the hide, the legs seem to crawl up between the nails which are placed about ten to fourteen inches apart, depending on the natural width of the legs.

In the preceding paragraph it was stated that the legs, when a fur hide is stretched, practically disappear, for the reason that in the first place fur hides are more flexible than leather hides because of a tanning process, and, secondly, because the legs on fur hides are cut off just above the knee, whereas in leather hides the whole leg is tanned and is a long narrow strip. The upper part of the legs on a leather hide will, of course, shift into the body of the hide very much the same as is the case with a fur hide, but the long shank will still remain, as of course it is beyond the range of the pull.

In connection with the several statements with respect to the positioning of the nails, it is to be understood that the nails are employed for connecting the hide to the frame.

It is thought that the many advantages of a frame for stretching and suspending hides, in accordance with this invention, can be readily understood, and although the preferred embodiment of the invention is as illustrated and described, yet it is to be understood that changes in the details of construction can be had which will fall within the scope of the invention as claimed.

What I claim is:

1. A frame for the purpose set forth comprising two pair of superposed spaced end bars, a pair of side bars each having one end thereof extending between the bars of a pair of end bars and fixedly secured therewith, the front bar of said pair of side bars projecting forwardly from the front ends of said pair of superposed end bars, a stationary inner bar having each end thereof extending between the bars of a pair of end bars and fixedly secured therewith, an adjustable inner bar having each end slidably mounted between the bars of a pair of end bars and constituting a hide stretching element, means for maintaining said adjustable bar in adjusted position, and a spindle projecting from each pair of end bars and disposed at the longitudinal center of the frame.

2. A frame for the purpose set forth comprising end and side bars fixedly secured together and a stationary and an adjustable inner bar, the front bar of said pair of side bars projecting forwardly from the front ends of said end bars, said stationary inner bar fixedly secured to said end bars and said adjustable bar slidably engaging with the

end bars and constituting a hide stretching element, means carried by the end bars for maintaining said adjustable bar in adjusted position, and a reinforcing yoke overlapping one side bar and having its ends fixedly secured to the other side bar intermediate the ends of the latter.

3. A frame for the purpose set forth comprising two pair of superposed spaced end bars, a pair of side bars each having one end thereof extending between the bars of a pair of end bars and fixedly secured therewith, the front bar of said pair of side bars projecting forwardly from the front ends of said pair of superposed end bars, a stationary inner bar having each end thereof extending between the bars of a pair of end bars and fixedly secured therewith, an adjustable inner bar having each end slidably mounted between the bars of a pair of end bars and constituting a hide stretching element, means for maintaining said adjustable bar in adjusted position, a spindle projecting from each pair of end bars and disposed at the longitudinal center of the frame, and a reinforcing yoke overlapping one side bar and having its ends fixedly secured to the other side bar intermediate the ends of the latter.

4. A frame for the purpose set forth comprising end and side bars fixedly secured together and a stationary and an adjustable inner bar, the front bar of said pair of side bars projecting forwardly from the front ends of said end bars, said stationary inner bar fixedly secured to said end bars and said adjustable bar slidably engaging with the end bars and constituting a hide stretching element, said adjustable bar interposed between said fixed inner bar and the rear bar, means carried by each pair of end bars for maintaining said adjustable bar in adjusted position, and a reinforcing yoke overlapping one side bar and having its ends fixedly secured to the other side bar intermediate the ends of the latter.

5. A frame for the purpose set forth comprising end and side bars fixedly secured together and a stationary and an adjustable inner bar, the front bar of said pair of side bars projecting forwardly from the front ends of said end bars, said stationary inner bar fixedly secured to said end bars and said adjustable bar slidably engaging with the end bars and constituting a hide stretching element, said adjustable bar interposed between said fixed inner bar and the rear bar, means carried by the end bars for maintaining said adjustable bar in adjusted position, a spindle projecting from each pair of end bars and disposed at the longitudinal center of the frame, and a reinforcing yoke overlapping one side bar and having its ends fixedly secured to the other side bar intermediate the ends of the latter.

6. A frame for the purpose set forth comprising two pair of superposed spaced end bars, a pair of side bars each having one

end thereof extending between the bars of a pair of end bars and fixedly secured therewith, the front bar of said pair of side bars projecting forwardly from the front ends of said pair of superposed end bars, a stationary inner bar having each end thereof extending between the bars of a pair of end bars and fixedly secured therewith, an adjustable inner bar having each end slidably mounted between the bars of a pair of end bars and constituting a hide stretching element, means for maintaining said adjustable bar in adjusted position, a spindle projecting from each pair of end bars and disposed at the longitudinal center of the frame, and a reinforcing yoke overlapping one side bar and having its ends fixedly secured to the other side bar intermediate the ends of the latter.

7. A frame for the purpose set forth comprising end and side bars fixedly secured together and a stationary and an adjustable inner bar, said stationary inner bar fixedly secured to said end bars and said adjustable bar slidably engaging with the end bars and constituting a hide stretching element, means carried by each pair of end bars for maintaining said adjustable bar in adjusted position, a spindle projecting from each pair of end bars and disposed at the longitudinal center of the frame, and a reinforcing yoke overlapping one side bar and having its ends fixedly secured to the other side bar intermediate the ends of the latter.

8. A frame for the purpose set forth comprising end and side bars fixedly secured together and a stationary and an adjustable inner bar, said stationary inner bar fixedly secured to said end bars and said adjustable bar slidably engaging with the end bars and constituting a hide stretching element, means carried by the end bars for maintaining said adjustable bar in adjusted position, said adjustable bar positioned between said stationary bar and the rear side bar of the frame, and said rear side bar being of materially less width than the forward side bar and constituting a connecting means when the frame is vertically suspended.

9. A frame for the purpose set forth comprising two pair of superposed spaced end bars, a pair of side bars each having one end thereof extending between the bars of a pair of end bars and fixedly secured therewith, a stationary inner bar having each end thereof extending between the bars of a pair of end bars and fixedly secured therewith, an adjustable inner bar having each end slidably mounted between the bars of a pair of end bars and constituting a hide stretching element, means for maintaining said adjustable bar in adjusted position, said adjustable bar positioned between said stationary bar and the rear side bar of the frame, and said rear side bar being of materially less width

than the forward side bar and constituting a connecting means when the frame is vertically suspended.

10. A frame for the purpose set forth comprising end and side bars fixedly secured together and a stationary and adjustable inner bar, said stationary inner bar fixedly secured to said end bars and said adjustable bar slidably engaging with the end bars and constituting a hide stretching element, means carried by the end bars for maintaining said adjustable bar in adjusted position, the forward side bar of said frame projecting forwardly from the pairs of end bars.
15. 11. A hide stretching frame comprising end and side bars fixedly secured together and a stationary and an adjustable inner bar, the rear side bar constituting a connecting means of a width to coact with a pick up device to suspend the frame with the hide secured to said inner bars and overlapping said front side bar in stretched condition, said front side bar projecting forwardly from the front ends of the end bars
20. up device to suspend the frame with the hide secured to said inner bars and overlapping said front side bar in stretched condition, said front side bar projecting forwardly from the front ends of the end bars
25. to overcome the formation of pockets in the hide when the latter overlaps said front side bar, said stationary inner bar fixed to the end bars and opposing said front side bar, said adjustable bar slidably connected with the end bars and opposing the rear side bar
30. the end bars and opposing the rear side bar

and constituting a hide stretching element, and means for maintaining said adjustable bar in adjusted position.

12. A hide stretching frame comprising end and side bars fixedly secured together 35 and a stationary and an adjustable inner bar, the rear side bar constituting a connecting means of a width to coact with a pick up device to suspend the frame with the hide secured to said inner bars and overlapping 40 said front side bar in stretched condition, said front side bar projecting forwardly from the front ends of the end bars to overcome the formation of pockets in the hide when the latter overlaps said front side 45 bar, said stationary inner bar fixed to the end bars and opposing said front side bar, said adjustable bar slidably connected with the end bars and opposing the rear side bar and constituting a hide stretching element, 50 and means for maintaining said adjustable bar in adjusted position, each of said end bars formed of a pair of spaced superposed complementary elements, and a spindle secured to the outer sides of each pair of members.

In testimony whereof, I affix my signature hereto.

ST. CLAIR EDE.
